UNITED STATES PATENT OFFICE.

THOMAS J. BURNS, OF SYRACUSE, NEW YORK.

WINDOW-SHADE.

1,352,350.

Specification of Letters Patent. Patented Sept. 7, 1920.

Application filed June 21, 1919. Serial No. 305,759.

To all whom it may concern:

Be it known that I, THOMAS J. BURNS, a citizen of the United States, residing at Syracuse, in the county of Onondaga and State of New York, have invented new and useful Improvements in Window-Shades, of which the following is a specification.

This invention relates to window shades or screens.

10 An object of the invention is to provide a novel form of guide, which may be used in connection with either a window shade or a window screen and which is carried upon the window to guide and hold the shade or screen in its adjusted position.

Another object of the invention is to provide a device of this character, which is neat and attractive in appearance, inexpensive to manufacture, and which may be easily 20 and quickly applied.

Other objects and advantages of the invention will appear as the following description is read in connection with the accompanying drawings.

25 In the drawings:

Figure 1 is an elevation of a car window, with the invention applied thereto.

Fig. 2 is a vertical sectional view of the same.

30 Fig. 3 is an enlarged section through one end of one of the curtain rods and guide.

Fig. 4 is a similar view of one of the wear plates.

35 Fig. 5 is a detail section showing the spring actuated latch.

Fig. 6 is a detail section showing the spring actuated latch.

Referring to the drawings in detail, there is illustrated a car window, which is designated by the reference character 10.

40 Mounted in suitable brackets 11, secured in position at the upper end of the window, is a spring actuated shade roller 12, the latter carrying a shade 13 of suitable size and fabric. Secured to the lower end of the shade 13, is a frame 14, which comprises transversely extending rods 16 and connecting bars 17. The rods 16 are preferably of tubular telescopic formation, so as to adapt 45 them to windows of different widths. Each end of these rods is flattened, as indicated at 18, the flattened portions being slightly offset and having their extremities formed with eyes 19.

55 A tubular guide 20 is secured to the inner face of each side of the window by

means of screws or other suitable fastening devices 21, the said guides being formed with open longitudinal slots extending their full length and adapted to receive the hems 60 22' on opposite side edges of the shade 13. Located within each of the tubular guides 20 is a rod 23 which is secured at its lower end to said guides and is spaced therefrom to permit of the free movement of the shade or 65 curtain 13. These rods are fitted within the hems of the shade or curtain and are of considerably larger diameter than the width of the slots 22 so that they not only guide the shade or curtain, but prevent its marginal edges from coming out of the tubular 70 guide members. The eyes 19 of the rod 16 receive the guide rods 23, so that the shade is guided and held within the tubular guides 20 when it is raised or lowered. The lower 75 rod 16 of the frame is provided at each end with a wear plate or strip 25, which surrounds the edge of the curtain and prevents wear upon the latter from contact with the edges of the slot 22 in the tubular guide 20. 80

The upper rod 16 of the frame is provided at each end with a spring actuated latch 26, which operates within the rod. One end of the latch extends through the end of the rod for engagement with spaced 85 notches provided in the tubular guide 20, while the opposite end of the latch carries an operating handle 27, which extends through a slot in the rod 16. By this means the curtain may be held in adjusted position, 90 while the formation of the frame insures a smooth working of the rods 16 upon the guide rods 21, by preventing the eyes 19 from binding.

Having described the invention, what is 95 claimed is:

1. The combination with a spring actuated window shade having side hems and a transverse hem, of a longitudinally slotted guide secured to each side of the window 100 casing, vertical rods positioned within said guides for insertion within the side hems, a rod positioned in the transverse hem and having each end engaged with the vertical rod and means extending over the side hems 105 of the shade and around the vertical rods to space the curtain hems from the tubular guides.

2. The combination with a spring actuated window shade having side hems and 110 a transverse hem, of a longitudinally slotted guide secured to each side of the window

casing, vertical rods positioned within said guides for insertion within the side hems, a rod positioned in the transverse hem and having each end engaged with the vertical rods and wear plates extending over the side hems of the shade and around the vertical rods to space the hems from the tubular guides.

3. The combination with a spring actuated window shade having side hems and a transverse hem, of a longitudinally slotted guide secured to each side of the window

casing, vertical rods positioned within said guides for insertion within the side hems, a frame comprising spaced transversely disposed rods and end connecting rods located within the transverse hem, eyes located at each end of the frame for engagement around the vertical rods and means extending over the side hems of the shade and around the vertical rods to space the hems from the tubular guides.

In testimony whereof I affix my signature.
THOMAS J. BURNS.
